UNITED STATES PATENT OFFICE

JOSEPH L. CASSIELL, OF NEW YORK, N. Y., ASSIGNOR TO WIRED RADIO, INC., OF NEW YORK, N. Y., A CORPORATION OF DELAWARE

SECRET WIRED RADIO TRANSMISSION SYSTEM

Application filed October 20, 1930. Serial No. 489,772.

My invention pertains in general to systems for transmission of high frequency signals and specifically relates to a wired radio system for transmission and reception of high frequency signals in which means are provided to prevent theft of signals by persons other than those for whom the signals were originally intended.

In the system of wired radio broadcasting in which modulated high frequency currents are impressed upon commercial light and power distribution networks, the light and power lines extend to many consumers who subscribe only to the light and power service and not to the wired radio service. It is therefore desirable that means be provided to prevent the intelligible reception of wired radio signals by consumers other than those who are authorized to receive such signals and who have proper wired radio receiving apparatus.

One of the objects of my invention consists in providing a system for the transmission and reception of high frequency signals in which means are provided for transmitting an intelligible audible frequency band and an unintelligible, or noise modulated, frequency band and in which receiving means are provided which are responsive only to the intelligible frequency band.

Another object of my invention consists in producing a secret wired radio transmission system in which an intelligible and an unintelligible frequency band are transmitted over a commercial light and power distribution network and in which means are provided which are adapted to receive only the intelligible frequency band.

Another object comprises producing a secret wired radio transmission system having transmitting means adapted to intelligibly modulate a definite portion of a frequency spectrum while unintelligibly modulating another portion of the frequency spectrum, and receiving means responsive only to the intelligibly modulated portion of the frequency spectrum.

A further object consists in providing a secret wired radio transmission system in which intelligible modulating currents and

unintelligible modulating currents are transmitted by a single carrier current and in which receiving means are provided which are responsive only to the intelligible modulating currents transmitted by the carrier.

I accomplish the above desirable objects in a novel system for transmission and reception of wired radio signals having means for transmitting intelligible and unintelligible audible frequencies by means of a single carrier current, and receiving means responsive only to the intelligible audible frequencies transmitted by the carrier current.

In the drawings which accompany and form a part of the specification and in which like reference numerals designate corresponding parts throughout:

Fig. 1 is a diagrammatic representation of one embodiment of the secret wired radio transmission system of my invention;

Fig. 2 is an elevation of apparatus used in the embodiment of Fig. 1 for varying the negative biasing potential of a thermionic tube;

Fig. 3 is a graphical representation of the transmission response of the apparatus used in my invention; and

Fig. 4 is another graphical representation of the transmission response of the apparatus used in my invention.

Referring to the drawings in detail, and particularly to Fig. 1, an oscillator 1 comprises a source of high frequency oscillations which are directed to a power amplifier 2. A modulator 3 under control of a microphone 4 directs modulating currents to the power amplifier 2 to modulate the oscillations, or carrier current from the oscillator 1 in accordance with intelligible sound waves, such as speech and music, picked up by the microphone 4. The output of the power amplifier 2 is fed to the band-pass filter systems 5 and 6. The band-pass filters 5 and 6, here shown, are of the inductively coupled mesh type. However, other types of filters employing different networks to accomplish the desired results may be used, if preferred, without departing from the scope of my invention.

Fig. 3 is a graphical representation of the

combined transmission response of filters 5 and 6, the cut-off frequencies for filter 5 being represented by f_3 and f_1 , while the cut-off frequencies for filter 6 are represented by 10 f_2 and f_3 . The filter 5 is, therefore, responsive to, and will pass only, frequencies within the band represented by f_3-f_1 , and the filter 6 is responsive to, and will pass only, frequencies within the band represented 15 represented by f_2-f_3 . In Figs. 3 and 4 the carrier frequency is represented by "C" at a point on the frequency spectrum within the unattenuated frequency band adjacent the lower cut-off frequency f_1 . As contemplated by my invention, the audible frequencies under control of microphone 4 are restricted to the frequency band f_3-f_1 , while the frequency band f_2-f_3 is employed to transmit unintelligible sounds which will guard the adjacent frequency band f_3-f_1 and prevent its reception by other than the proper receiving apparatus.

Referring again to Fig. 1, it will be seen that the output of the filter 6 is directed to 25 the grid of the thermionic tube 7 and to a variable resistor 8, as shown. The resistor 8 is in series with a battery 9 which serves as a source of negative biasing potential for the grid of the tube 7. The battery 9 is connected to the negative side of the filament of 30 the tube 7. Battery 10 is provided as a source of filament supply for the tube 7. A battery 11 is connected through inductance 12 to plate of the tube 7 and serves as a source 35 of plate potential. The inductance 12 forms part of another filter 13 which is similar to filter 6 and is responsive to frequencies within the band f_2-f_3 (see Fig. 3). This filter 13 is provided on the output side of the tube 7 to 40 attenuate harmonic frequencies developed by the tube and to insure that the output is within the desired frequency range.

The output of filters 5 and 6 are connected, 45 respectively, through capacitive couplings 14 and 16 to power lines 17. The power lines 17 extend from a source of commercial light and power current 18 and are indicative of a normal light and power distribution network. The capacitive couplings 14 and 16 allow 50 the passage of high frequency currents to the lines 17 but prevent the commercial power, which is of low frequency, from feeding back into the high frequency filter systems.

A receiving filter system 19 is connected 55 through capacitive couplings 20 to the power lines 17. The filter system 19, here shown, is of the inductively coupled mesh type. However, as before stated, other types of filter networks may be employed. The filter 60 19 has a transmission response graphically represented in Fig. 4, the upper cut-off frequency being represented by f_3 , the lower cut-off frequency being represented by f_1 . It is evident, then, that the filter 19 is responsive 65 to, and will pass only, frequencies in the

band f_3-f_1 , and the frequencies within the band f_2-f_3 , as well as all others, will be rejected. The filter 19, therefore, is responsive only to frequencies passed by the transmitter filter 5 represented by the frequency band f_3-f_1 in Fig. 3. The output of the filter 19 is fed to a receiver 21 having a normal detector and amplifier system adapted to reproduce the acoustical vibrations picked up by the transmitter microphone 4.

Fig. 2 illustrates the construction of mechanical parts associated with the variable resistor 8 which controls the negative grid biasing potential of the tube 7. The resistor 8, in the form of an insulating tubing having 75 helically wound resistance wire thereon, is positioned between two upright members 22 and 23. The upright members 22 and 23 are mounted upon a base 27. A guide rod 24 is mounted between the upright members 22 and 23 parallel with the resistor 8. A rider 25, composed of insulating material, such as 80 fibre, is reciprocatively positioned on the guide rod 24. A contact spring 26 is mounted on the rider 25 so as to slidably engage 85 the resistance wire of the resistor 8. A motor 28 is mounted on the base 27 and has a crank-disk 29 mounted upon one end of its armature shaft 30. A connecting rod 31 is 90 pivotally connected at one end to the rider 25 and at the other end to an eccentric point of the disk 29. Rotation of the armature shaft 30 causes a corresponding rotation of the disk 29 which imparts a reciprocating 95 movement to the rider 25 thereby periodically varying the effective resistance value of the resistor 8.

The operation of the foregoing is as follows:

Intelligible sound waves impinged upon the microphone 4 act through the modulator 3 to modulate the high frequency oscillations, or carrier current, produced by the oscillator 1. This modulated carrier current is properly amplified by the amplifier 2 and 100 fed into the filter systems 5 and 6. The filter 5 rejects all frequencies except those within the frequency band f_3-f_1 , as shown in Fig. 3. The filter 6 rejects all frequencies except 105 those within a frequency band f_2-f_3 , shown in Fig. 3. The output of the filter 5 is fed through capacitive couplings 14 to the power lines 17, while the output of the filter system 6 is fed into the tube 7. The value of the 110 grid biasing potential of the tube 7 fed through the resistor 8 is altered at audible frequencies by varying the effective value of the resistor 8. This is accomplished by causing contact spring 26 to move back and forth along the resistance wire of the resistor 8. This periodic increase in grid biasing potential 115 serves to periodically block the tube 7 by increasing the negative charge on the grid thereof. Such action produces an unintelligible, or noise, modulation of the signals 120

from filter 6 and which is of an audible frequency dependent upon the speed of rotation of motor 28. The output of the tube 7 is then fed through another filter 13 similar to 5 filter 6 and thence through capacitive couplings 16 to the power lines 17. The filter 13 insures restriction of the frequencies to within the band f_2-f_3 of Figs. 3 and 4. The total, or combined, filter transmission output 10 therefore extends over the band f_2-f_1 in Fig. 3, in which the band f_3-f_1 is intelligible while the band f_2-f_3 is unintelligible.

The receiving filter 19 and the receiver 21 receive the intelligible signals lying within 15 the band f_2-f_3 . Other receiving apparatus, not having filter systems of the same characteristics as filter system 19, have a comparatively broader response, such as graphically represented by the curve "r" in 20 Fig. 4. It is evident that such a receiver would not be able to distinguish between the frequency bands f_2-f_3 and f_3-f_1 . The resultant reception is therefore rendered unintelligible by the presence of the unintelligible, or noise modulated, frequencies within 25 in the band f_2-f_3 .

By such a system, then, it is possible to maintain secret distribution of signals over commercial light and power distribution 30 lines to only those authorized subscribers who are equipped with proper receiving apparatus having filters of predetermined characteristics.

Although I have shown a preferred embodiment of my secret wired radio transmission system, it is, of course, to be understood that changes can be made therein without departing from the intended scope of my invention. I do not, therefore, desire to 40 limit myself to the foregoing except insofar as may be pointed out in the appended claims.

What I claim as new and original and desire to secure by Letters Patent of the United 45 States is:

1. A transmission system comprising, in combination, a source of carrier current, means adapted to modulate said carrier current at audible frequencies, a filter system responsive to high frequency current within a predetermined frequency band, a second filter system responsive to high frequency current within a predetermined frequency band different from said first-mentioned frequency 50 band, a thermionic tube having grid and plate electrodes, a connection between the output of said second filter and the grid of said thermionic tube, a source of biasing potential for said grid, means adapted to periodically 55 vary the value of said biasing potential, a third filter responsive to high frequency current within the frequency band to which said second filter is responsive, a connection between the plate of said thermionic tube and 60 said third filter system, and receiving means 65

responsive only to high frequency current within the frequency band to which said first-mentioned filter is responsive.

2. A transmission system comprising, a source of carrier current, means adapted to 70 modulate said carrier current at audible frequencies, a filter system responsive to high frequency current within a predetermined frequency band, a second filter system responsive to high frequency current within a pre- 75 determined frequency band different from said first-mentioned frequency band, a third filter in series with said second filter and re- 80 sponsive to high frequency current within the same frequency band to which said second filter is responsive, means interposed between said second and said third filter systems and adapted to unintelligibly, or noise, modulate the high frequency current passed by said first-mentioned filter, and receiving means re- 85 sponsive only to high frequency current within the frequency band to which said first-mentioned filter is responsive.

3. A transmission system in accordance 90 with claim 2, but in which wire lines are provided from said first and third filters to said receiving means.
